DRAINAGE OF FLOATING ROOFS

Edgar E. Shanor, Sharon, Pa., assignor to The
Petroleum Iron Works Company of Ohio,
Sharon, Pa., a corporation of Ohio

Application December 21, 1932, Serial No. 648,282

5 Claims. (CL 220—26)

The invention has to do more particularly with oil storage systems of the floating roof type. With such systems it has been, for many years, more or less conventional practice to provide 5 facilities for draining excess accumulation of water on the roof such as may follow cloudbursts or unusually heavy rainfalls, it being obvious that the roof may collapse or otherwise be seriously damaged by such sudden accession of 10 weight. Some of these drainage practices are good and some are wholly impracticable and most of them suffer the disadvantage that they are complicated and, hence, costly in installation and maintenance.

15 The principal object of the present invention is to provide for drainage of floating roofs in an efficient and simple way and in such way as will appreciably reduce the cost of installation, obviating the necessity of frequent repairs and so appreciably reduce the cost of upkeep; to provide 20 for drainage via the fluid content of the storage space and without the hazard of the fluid content, or its volatiles, making egress through the drain.

25 The nature, characteristic features and scope of the invention more readily will be understood from the following detailed description taken in connection with the accompanying drawing, wherein

30 Figure 1 is a sectional elevational view of a drainage system embodying the invention and showing, in diagram, means for priming the system.

35 Fig. 2 is a vertical sectional view of the drainage system showing in detail the manner of assembly.

Fig. 3 is a sectional detail of the end connection between the trap and the drain pipe, and

40 Fig. 4 is a sectional elevational view of the device employed in removing air pockets in priming the system.

In the drawing, 5 represents the floating roof, the organization and details of which may be as usual except as departed from in carrying the 45 invention into practice. 6 represents the collecting basin or sump which as usual may be disposed axially of the floating deck or roof, or wherever there is provision for natural drainage.

The sump or basin 6 comprises a bottom wall 7 and a side wall 8 connected by weld deposit metal 9, the side wall having a top offset 10 secured by weld deposit metal 11 and affording a ready tie to facilitate field application to the deck 5 as by weld deposit metal 12.

45 The bottom wall of the sump is provided with

an opening 13 in which is stepped a collar or sleeve 14 anchored as by weld deposit metal 15 and effective as a support for a depending drainage pipe 16 and the upward extension 17 thereof. The depending straight leg or drainage pipe 16 has co-extensive therewith an S strap 18.

It is a merit of the invention that the trap is inexpensively formed of duplicate semi-circular bends 19 and 20 connected by weld deposit metal 21. Bend 19 is joined to the straight leg 16 by 10 weld deposit metal 22 and bend 20 has a depending straight leg portion 23 joined thereto by weld deposit metal 24. Outlet 23 is adapted for the temporary reception of a cap 25. So also the riser or straight pipe extension 17 is provided 15 with a removable cap 26. The sleeve or collar 14 ranges upwardly in the sump or basin and is substantially the depth thereof and constitutes an overflow to lead excess drainage into the depending straight leg of the drainage system. Element 14 is of relatively heavy or sturdy construction and lends strength and adequate support to the drainage system. It will be understood that when the system is properly functioning the riser or upper pipe extension 17 is removed from the overflow element.

In priming the drainage system, the caps on the terminal end of the trap and on the head of the riser are removed and water is supplied to the drainage system up to a point indicated by the 30 line X—X, whereupon the trap closure is replaced and screwed water-tight and the system is replenished with water until it is practically filled and the cap on the riser is replaced in air-tight relation. The lower cap is then removed, 35 the effect of which is to permit water to the right of line W—W to run out while, if the cap on the riser is in proper sealing relation, the water to the left of line W—W will remain in the drain.

40 The roof is now ready for floating. When the roof floats there will be an air pocket at C. After the roof is floated, the cap on the riser is removed and the air pocket is dissipated or destroyed in any suitable way. One expedient which has proven eminently satisfactory is to insert a sound or searcher S comprising a straight stem or a rigid portion and a flexible advanced portion and an external valve or petcock V, 50 through the medium of which the pocketed air is allowed to escape.

45 The air remover is then detached and a check is made to see if the water in the drain has fallen below line Y—Y and if it has, the upper pipe 55

extension or riser 17 may be removed whereupon the drain is ready for operation.

It will be understood that this drain is to be used in cases where the contents of the tank consist of liquid lighter than water and for this reason a water seal or trap is employed to prevent the liquid from rising through the drain to the roof.

Crude oil, as it comes from the well, contains 10 heavy sediment which settles to the bottom of the tank and is heavier than water and is known to the industry as "B. S.". When oil is being pumped into the tank the sediment circulates throughout the tank. If the drain is open to 15 ward the roof and does not have the reverse U extension of my invention the sediment can settle into the drain and interfere with its function. There is also the possibility of there being sediment and heavy matter in stored refined oil or 20 in gasoline. With the reverse extension no heavy matter can settle in the drain and there can be no obstruction in the drain such as will interfere with normal drainage.

The reverse extension is also functionally important in that it serves to direct the flow of 25 drainage from the roof toward the bottom of the tank thereby causing the drainage to settle to the bottom quicker than it otherwise would.

The invention has been in use in the oil fields 30 and in other sections for a sufficient period of time to satisfy the industry that it will function under conditions that would overtax the conventional drainage systems. It has been demonstrated that the trapped air does not need to be 35 removed. It washes out with the flow of the water. On the pontoon type of floating roof the water would draw off without the siphon seal because it has sufficient head above the oil, but the drain would empty itself of water and expose 40 the liquid in the pipe (the contents of the tank) to evaporation. With the siphon seal of my invention that cannot occur. It is obvious that the vertical leg connecting with the roof will have in it a column of water high enough to balance the 45 pressure of the tank liquid in the other leg, but this is true only because of the reverse bend. When the water in the vertical leg becomes higher than that necessary to balance the liquid pressure on the other leg water flows through the 50 drain. Manifestly, if the liquid in the tank is lighter than water the level of the water in the vertical leg will be below the roof level and the roof will be dry. The greater the difference in specific gravity the lower the water will stand in 55 the leg. This and the length of the leg determines the number of inches or feet the water in the leg is below the top of the roof, it being under-

stood that the roof is floating on the liquid in the tank.

Without the reverse U bend no water would be held in the vertical leg. Consequently it will receive the volatiles of the tank and being open 5 at the top will lose the volatiles by evaporation and withal will present a tremendous fire hazard.

Having described the invention, what is claimed is:—

1. In storage tanks of the float closure type, 10 the combination of a floating roof having a drainage collecting basin equipped with an overflow having fixed and movable pipe extensions, whereof one is a depending drain pipe and whereof the other is a factor for priming purposes, and 15 a double U trap terminating the drain pipe, and providing a liquid seal that is effective to prevent rise of the liquid contents of the tank in the drain pipe.

2. In combination, a storage tank for volatiles, 20 a roof for floatwise support upon the contents of the tank and having a drainage sump, and a drain pipe depending from the sump and terminating in reverse bends whereby a water column is maintained in the vertical leg to balance tank 25 pressure in the other leg.

3. In combination, a storage tank for volatiles, 30 a roof for floatwise support upon the liquid contents of the tank and having a drainage sump, and a drain pipe depending from the sump and continued as reversely disposed U bends effective to prevent sediment from interfering with drainage and to insure a sufficient column of water in the vertical leg to overcome or balance the tank pressure in the drain. 35

4. In combination, a storage tank for volatiles, 40 a roof for floatwise support upon the liquid contents of the tank and having a drainage sump, and a drain comprising a straight leg depending from the sump and continued as a reverse extension having an opening directed towards the bottom of the tank whereby a column of water is maintained in the straight leg to balance pressure in the extension.

5. Means, for draining floating roofs of oil storage tanks, comprising, in combination, an oil storage tank, a floating seal having a drainage collecting device, a drain pipe in communication therewith and discharging directly towards the bottom of the tank, there being a reverse 45 connection intermediate the vertical leg of the drain and its point of discharge whereby a volatile sealing column is maintained in the vertical leg which varies according to the specific gravity of the liquid contents of the tank. 55
